EXTENSION COUCH

Reginald A. Ferguson, Lakeside, Quebec, Canada,
assignor, by mesne assignments, to Simmons
Company, New York, N. Y., a corporation of
Delaware

Application May 6, 1935, Serial No. 20,087
In Canada April 6, 1935

9 Claims. (Cl. 5—17)

This invention relates to improvements in extension couches or lounges and an object of the invention is to provide an extension couch or lounge having a back with or without arm rests readily movable to an inoperative position when the couch is extended. Another object is to provide a locking device for the couch sections which is substantially automatic in operation to unlock the sections when it is desired to extend the couch but which retains the couch sections locked together under other conditions. Various other objects and the advantages of the invention may be ascertained from the following description and the accompanying drawing.

In its preferred embodiment, the invention consists in providing the outer movable section of an extension couch with a back pivotally connected to the ends of said outer section at a point approximately midway between the front and back of the section, the said back being adapted to swing forward to inoperative position when the couch is to be extended and when so swung forward to be used as a handle for moving the outer section relatively to the inner section. The points of attachment of the back to the couch outer section are such that when the back is used as aforesaid, sufficient lifting effort is applied unconsciously to the couch section to initiate unlocking action of the locking mechanism which normally connects the outer and inner couch sections when the couch is closed.

In greater detail the invention consists of the novel features and combinations of features herein described and disclosed in the accompanying drawing together with all such novel equivalents therefor and modifications thereof as are within the scope of the appended claims.

In the accompanying drawing which illustrates that embodiment of the invention now preferred, but to the details of which the invention is not confined,

Fig. 1 is an end elevation of an extension couch embodying the invention.

Fig. 2 is a plan view of the couch on a reduced scale.

Fig. 3 is an elevation of that form of locking mechanism now preferred.

Referring more particularly to the drawing, 11 and 12 designate the frames of outer movable and inner stationary couch sections, respectively.

These frames may be of any suitable construction and are not limited to the conventional metal construction illustrated. The frames are provided with longitudinal members 13 and 14, respectively, which may be front rails, as illus-

trated, or may be otherwise disposed. A latching or locking means is mounted on one of said members 13 or 14 for engagement with the other to releasably lock the couch sections together in their closed or nested relation. This latching or locking may be, conveniently, an arm 15 rigidly connected to one of the members, for instance the member 13, and adapted to overlie the other of said members, 14, and provided with a roller 16 adapted to engage that edge of the member 14 which is remote from the member 13, the roller being preferably so located that its axis is on a level with or slightly above the point of contact with the frame member 14. Any other suitable form of locking mechanism may be used.

The couch is provided with a back of any suitable construction pivotally connected to the outer moving section 11. The most simple form of back is illustrated and comprises a horizontal member 17 and end members 18 rigidly connected to the member 17 and pivotally connected to the ends of the frame 11 approximately midway between the front and back thereof, as by means of studs shown at 19. According to the present invention the back end members are preferably curved so that the lower portions thereof are only slightly inclined with reference to the top rails 20 of the ends of the frame 11. The connection between the back ends 18 and the frame ends is preferably by means of brackets 21 bolted or riveted to the end top rails 20 and carrying the studs 19 which support the back ends. The lower edges of the brackets are provided with outwardly projecting flanges 22 on which the back ends may rest when the back is in use as such. The studs 19 engage the back ends some distance from the ends thereof, as shown, and the adjacent portions of the flanges 22 are downturned as at 23 to form stops for engagement by the lower portions of the back ends to prevent excessive forward movement of the back.

The back ends may be provided with arm rests of any suitable form as indicated at 24.

If the couch frame 11 is provided with upholstery boards at the ends, as shown at 25, these are interposed between the brackets 21 and the frame end rails 20 and the brackets are bolted or riveted through the upholstery boards to the end rails so as to obtain the desired rigidity of attachment.

When the couch is to be opened, the back is swung forward from its normal position indicated by broken lines to the position indicated by full lines, Fig. 1, and is used as a handle to draw the outer couch section forward. In this

operation the operator unconsciously applies a certain lifting effort to the outer couch section sufficient to enable the roller 16 to ride over the front rail of the stationary section 12 and thereby 5 unlock the sections. This effect is believed to result from the moving force being applied in substantially the direction of the arrow 26 and produces an apparently effortless, automatic unlocking of the couch sections. If a horizontal pull 10 is applied to the couch, as indicated by the arrow 27 the sections are unlocked with difficulty or not at all, depending on the location of the roller with reference to the rail 14.

When the locking mechanism is at the front 15 of the couch, it is preferred to locate the studs 19 somewhat nearer the front of the couch than the back and vice versa.

The arrangement herein described, in addition to providing a novel combination of outer 20 moving couch section and back pivoted thereto provides an automatic unlocking means which avoids the necessity of stooping and lifting the front of the outer section or of specially manipulating the locking means while drawing out the 25 couch section, as is customary.

Having thus described my invention what I claim is:—

1. An extension couch comprising an outer 30 movable section, an inner stationary section, a roller carried by one of said sections and adapted to over-ride a portion of the other section and engage the same with locking effect when the couch is closed and a back pivotally connected to said outer section and adapted for movement to 35 a position in which it may be used to draw out the outer section and to simultaneously apply such lifting force to the outer section as will initiate disengaging movement of the roller and the section engaged thereby.

40 2. An extension couch comprising an outer movable section, an inner stationary section, locking means carried by one of said sections and engageable with the other section to releasably secure the sections in their closed relation and 45 capable of releasing said sections by a lifting action of the movable section, and a back pivotally connected to said outer section and movable to an inoperative position to form a handle for applying lifting effort to the outer section to actuate 50 said locking means and for withdrawing said outer section.

3. An extension couch comprising an outer 55 movable section, an inner stationary section, locking means carried by an edge portion of one of the sections and engageable with the corresponding edge portion of the other section to releasably secure the sections in their closed relation and capable of releasing said sections by a lifting action of the movable section, and a back pivotally 60 connected to the outer section and movable to a forward position to form a handle for applying lifting effort to the outer section to release said locking means and for withdrawing said outer section.

65 4. A couch comprising a seat carrying section, a back including a longitudinal member and end members having forwardly extending substantially horizontal lower portions pivotally connected to said section at points spaced from the ends 70 of said end members, supports on said section engageable by said end members between the pivotal points and the longitudinal member to support the back in operative position, and further supports engageable by said end members between 75 the pivotal points and the ends of the members

to support the back in forward inoperative position.

5. An extension couch comprising normally telescoped inner and outer sections, the inner section being normally stationary and the outer section being transversely movable substantially horizontally to extended position relative to said inner section so as to be adapted to cooperate with the latter to form a bed of superior size, and a back comprising a longitudinal member and supporting upstanding end members rigidly connected to said longitudinal member, said end members having their lower ends mounted on said movable section so as to permit swinging movement of said longitudinal member forwardly 10 of the outer section to a position clear of the sleeping surface thereof, said longitudinal member, when in a forward position, constituting a handle for facilitating forward movement of said outer section. 15

6. An extension couch comprising normally telescoped inner and outer sections, the inner section being normally stationary and the outer section being transversely movable substantially horizontally to extended position relative to said 20 inner section so as to be adapted to cooperate with the latter to form a bed of superior size, a back including a longitudinal member spaced from said outer section and end members connected to said longitudinal member and pivotally 25 connected to said outer section at points substantially spaced from the front and rear edges of said section, said longitudinal member being thereby adapted to be swung to a position forwardly of the outer section and clear of the 30 sleeping surface thereof and constituting a handle for drawing said outer section forwardly, and means for supporting said back in normal back position.

7. An extension couch comprising normally 40 telescoped inner and outer sections, the inner section being normally stationary and the outer section being transversely movable substantially horizontally to extended position relative to said inner section so as to be adapted to cooperate 45 with the latter to form a bed of superior size, a back including a top rail member spaced from said outer section and end members rigidly secured to the rail member and pivotally connected to the outer section at points substantially spaced 50 from the front and rear edges of said section, said top rail member being thereby adapted to be swung to a position forwardly of the outer section and clear of the sleeping surface thereof and constituting a handle for drawing said outer 55 section forwardly, and means for supporting said back in normal back position.

8. An extension couch comprising normally telescoped inner and outer sections, the inner section being normally stationary and the outer section being transversely movable substantially horizontally to extended position relative to said inner section so as to be adapted to cooperate with the latter to form a bed of superior size, a back including a longitudinal member spaced 60 from said outer section and end members connected to said longitudinal member and pivotally connected to said outer section at points substantially centrally between the front and rear edges thereof, said longitudinal member being thereby 65 adapted to be swung to a position forwardly of the outer section and clear of the sleeping surface thereof and constituting a handle for drawing said outer section forwardly, and means for supporting said back in normal back position. 70

9. An extension couch comprising normally telescoped inner and outer sections, the inner section being normally stationary and the outer section being transversely movable substantially horizontally to extended position relative to said inner section so as to be adapted to cooperate with the latter to form a bed of superior size, a back including a longitudinal member spaced from said outer section and end members connected to said longitudinal member and pivotally connected to said outer section intermediate the front and rear edges thereof, said longitudinal member being thereby adapted to be swung to a position forwardly of the outer section and clear of the sleeping surface thereof and constituting 5 a handle for drawing said outer section forwardly, and means carried by said outer section and engageable with said end members for supporting said back in normal back position.
